UNITED STATES PATENT OFFICE.

CHARLES W. GRAY, OF CHATTANOOGA, TENNESSEE.

STAMPING-MACHINE.

No. 845,775.

Specification of Letters Patent.

Patented March 5, 1907.

Application filed February 27, 1905. Renewed December 3, 1906. Serial No. 346,165.

To all whom it may concern:

Be it known that I, CHARLES W. GRAY, a citizen of the United States, residing at Chattanooga, in the county of Hamilton and State of Tennessee, have invented a certain new and useful Improvement in Stamping-Machines, of which the following is a full, clear, concise, and exact description, reference being had to the accompanying drawings, forming a part of this specification.

My invention relates to machines for sealing envelops and applying postage-stamps thereto, and has for its general object the provision of a machine of an improved construction and design that will very effectively operate to perform these functions.

More specifically my invention has for one of its objects the provision of a machine of the class described whereby envelops may effectively be sealed notwithstanding the bulk of their contents within the range of the mechanism and the stamps effectively applied thereto. To this end I employ a sectional plunger that desirably, though not necessarily, is depressed by a pivoted lever, one section of the plunger being contractible while the other is preferably not contractible. One of the sections of the plunger serves to operate a stamp-applying plate, while the other serves to operate a plate adapted to seal the envelops. The stamp-applying plate and the plate for sealing the envelops move in opposite directions, to which end a supporting-plate for the envelops to be sealed and stamped is interposed between the same, the stamp-applying plate desirably working through an opening in this supporting-plate, so that as the hand-lever is rotated the envelop-sealing plate is moved downward toward said foundation-plate and the stamp-applying plate is moved upward through an opening in said foundation-plate. This opening in the foundation-plate may, with the stamp-applying plate moving therein, constitute the magazine for the stamps, and in order that the stamps may be applied and the envelop sealed the flaps of the envelops and the portions of the envelops that are to receive the stamps are moistened through the agency of any suitable moistener, whereafter the envelop is interposed between the sealing-plate and the stamp-affixing plate and the lever operated to seal and stamp the interposed envelop. The non-contractible section of the plunger is preferably fixed to

the sealing-plate, while the contractible section of the plunger preferably effects the operation of the stamp-affixing plate.

It is another object of my invention to provide accessibility to the magazine for the stamps, to which end the mounting for the plunger is displaceable, said plunger-mounting being desirably hinged to the aforesaid foundation-plate, whereby whenever it is desired to load the stamp-magazine, (whose walls are the walls of the opening in the foundation-plate and whose bottom is the movable stamp-affixing plate,) the mounting for the plunger may be swung back. The section of the plunger that is contractible desirably has separable engagement with the stamp-affixing plate, while a restoring-spring is desirably provided for the entire plunger to elevate the sealing-plate and permit restoration of the stamping-plate. The pin forming a part of the mechanism directly coöperating with the stamping-plate projects through the foundation-plate, while the plunger carries an ear or an extension that projects rearwardly sufficiently to permit engagement thereof with the said pin, the said ear desirably having a downward projection for engaging the said pin.

I will explain my invention more fully by reference to the accompanying drawings, in which—

Figure 1 is a front elevation of a machine constructed in accordance with my invention. Fig. 2 is a plan view thereof. Fig. 3 is a plan view with the plunging mechanism removed. Fig. 4 is a detail view, partially in section and partially in elevation, showing the plunger and parts immediately associated therewith. Fig. 5 is a view in elevation and partially in section, showing the plunging mechanism swung to one side. Fig. 6 is a cross-sectional view on line *a* *a* of Fig. 7. Fig. 7 is a view in elevation, partially in section, of that much of the mechanism appearing in Fig. 6. Fig. 8 is an end elevation, partially in section, showing the plunger in its vertical position. Fig. 9 is a sectional plan view illustrating the magazine and the locking device for holding the plunger in a vertical position.

Like parts are indicated by similar characters of reference throughout the different figures.

The foundation-plate 1 that I have hitherto spoken of preferably constitutes the top of

a bottomless box that contains the stamp-applying mechanism and the mechanism whereby the plunger and the sealing-plate may be temporarily displaced. This foundation-plate has an opening 2, which is desirably flanged to afford a space in which postage-stamps may be received. In this space 2 there is a movable plate 3, that constitutes a bottom of a magazine that is thus established for the stamps. A spring-barrel 4 is preferably secured to the bottom of the plate 3, in which a spring 5 is received, that engages an intermediately-pivoted lever 6, said lever having its mounting in the side walls of the box containing the stamp-affixing mechanism. The end of the lever 6 opposite that engaging the spring 5 is articulated to a plunger-pin 7, which is operated by the mechanism hereafter to be set forth to effect a vertical movement of the elements 3, 4, and 5, whereby the topmost stamp may be applied to an envelop, this stamp issuing through the foundation-plate 1. In order that the stamp may be applied and the envelop at the same time sealed, there is provided a sealing-plate 8, upwardly from which projects an operating-plunger formed of the rod 9, a reduction 10 thereof, preferably screwed thereto, and a contractible section 11, preferably in the form of a coil-spring. In order that the spring 11 may be held and effectively united with the actuating element 12 that is to engage the pin 7, said spring 11 is desirably surrounded by a sleeve 13, slideable upon the section 9, and to which sleeve the element 12 is secured. The upper end of this sleeve has connected therewith a link 14, that is connected with the hand-lever 15, pivoted at one end to a vertical arm 16, the said hand-lever having a pin 17 working within a slot 18 in another vertical arm 18', whereby the said hand-lever may be guided in its rotation, said slot being concentric with the pivotal mounting for said hand-lever. The lower section 9 10 of the plunger has a foot-plate 19, in which there is provided a recess 20, in which recess a strap 21 may be contained, this strap being screwed to the sealing-plate 8, having a recess therein that receives the foot-plate 19. This connection between the stem and the sealing-plate is desirably so flexible as to permit a slight tilting of said plate, so that an envelop whose contents are not of uniform thickness may effectively be sealed. The element 12 preferably includes a downwardly-projecting pin 12', alined with the pin 7, but preferably separable therefrom. The plunger preferably has a tubular guide 22, that is made mechanically a part of the same structure that includes the arms 16 and 18'. This tubular guide 22 is closed at its bottom, and in the space afforded between the interior surface thereof and the part 10 a restoring-spring 23 is disposed, which is placed under compres-

sion when the plunger is moved downwardly and which spring upon its expansion restores the plunger.

When an envelop is to be stamped and sealed, its flap is moistened and also that portion of the address-surface that is to receive the stamp, whereafter it is interposed, address-face downward, between the sealing-plate 8 and the foundation-plate 1, whereafter the lever 15 is depressed, causing the plunger comprising the elements 9, 10, and 11 to be moved downwardly, whereby the said plate 8 is depressed and permitted to swing slightly in case the contents of the envelop are uneven in thickness. The downward movement of the plunger ultimately effects the upward movement of the stamp-affixing plate, which operation is desirably not commenced immediately upon the downward movement of the plate 8, on which account the elements 12' and 7 have separable engagement, so that there is a material depression of the plunger before the said elements 7 and 12' contact. The spring 11 permits of any required relative motion within the limits of the device between the element 12 and the plunger that will permit envelops having contents of varying thicknesses to be stamped and sealed. Where a restoring-spring is employed, it is made weaker than the spring 11 for an obvious reason.

The plate 8 overlies the stamp-magazine, and in order that the stamp-magazine may be made accessible for replenishing the same, the elements 16, 18, and 22 are provided with a hinged connection with the base of the device, as indicated most clearly in Figs. 2, 3, 5, 6, and 8. There are two catches 24 projecting through openings 25 in the plate 1 into engagement with teeth 26 upon a bar 27, maintained in locking engagement with said catches 24 by the spring 28, which engagement may be broken by the application of the thumb to the pin 29, projecting from the plate 27 through the slot in the base of the device, whereby the plunger and parts immediately associated therewith may be swung to the position indicated in Fig. 5 for the purpose of reloading the stamp-magazine or may be restored to the position shown in Fig. 8 to make the machine fully operative. In order that no moisture may accumulate within the stamp-magazine, a gutter 30 is provided about the stamp-magazine, which may have an outlet pitched downwardly for drainage.

It will be seen that while the sealing-plate is operated before the stamp-applying plate in the operation of sealing and stamping envelops the stamping-plate is removed before the sealing-plate, when the operating hand-lever is released, so that there is no tendency to remove the stamps from the stamp-box as the envelop is withdrawn, the only stamp taken being that applied to the

envelop. This result I am able to accomplish by reason of the separable connection between the stamp-plate and the plunger.

It is obvious that changes may readily be made in the preferred embodiment of my invention herein illustrated without departing from the spirit of the invention, and I do not, therefore, wish to be limited to the precise construction shown; but,

Having thus described my invention, I claim as new and desire to secure by Letters Patent—

1. An envelop sealing and stamping machine including a foundation-plate, a sealing-plate movable toward and from the said foundation-plate, a stamping-plate movable toward and from the sealing-plate, the envelop to be sealed and stamped being interposed between the sealing-plate on one side and the foundation and stamping plates on the other side, and an operating-plunger including in its formation a contractible section, one section of the plunger operating the stamping-plate and the other section of the plunger operating the sealing-plate.

2. An envelop sealing and stamping machine including a foundation-plate, a sealing-plate movable toward and from the said foundation-plate, a stamping-plate movable toward and from the sealing-plate, the envelop to be sealed and stamped being interposed between the sealing-plate on one side and the foundation and stamping plates on the other side, and an operating-plunger including in its formation a contractible section, one section of the plunger operating the stamping-plate and the other section of the plunger operating the sealing-plate, the stamping-plate having separable engagement with the section of the plunger operating the same to cause its movement subsequent to the movement of the sealing-plate as the envelop is being stamped and sealed.

3. An envelop sealing and stamping machine including a foundation-plate, a sealing-plate movable toward and from the said foundation-plate, a stamping-plate movable toward and from the sealing-plate, the envelop to be sealed and stamped being interposed between the sealing-plate on one side and the foundation and stamping plates on the other side, and an operating-plunger including in its formation a contractible section in the form of a spring, one section of the plunger operating the stamping-plate and the other section of the plunger operating the sealing-plate.

4. An envelop sealing and stamping machine including a foundation-plate, a sealing-plate movable toward and from the said foundation-plate, a stamping-plate movable toward and from the sealing-plate, the envelop to be sealed and stamped being interposed between the sealing-plate on one side and the foundation and stamping plates on

the other side, and an operating-plunger including in its formation a contractible section in the form of a spring, one section of the plunger operating the stamping-plate and the other section of the plunger operating the sealing-plate, the stamping-plate having separable engagement with the section of the plunger operating the same to cause its movement subsequent to the movement of the sealing-plate as the envelop is being stamped and sealed.

5. An envelop sealing and stamping machine including a foundation-plate, a sealing-plate movable toward and from the said foundation-plate, a stamping-plate movable toward and from the sealing-plate, the envelop to be sealed and stamped being interposed between the sealing-plate on one side and the foundation and stamping plates on the other side, and an operating-plunger including in its formation a contractible section in the form of a coiled spring, one section of the plunger operating the stamping-plate and the other section of the plunger operating the sealing-plate.

6. An envelop sealing and stamping machine including a foundation-plate, a sealing-plate movable toward and from the said foundation-plate, a stamping-plate movable toward and from the sealing-plate, the envelop to be sealed and stamped being interposed between the sealing-plate on one side and the foundation and stamping plates on the other side, and an operating-plunger including in its formation a contractible section in the form of a coiled spring, one section of the plunger operating the stamping-plate and the other section of the plunger operating the sealing-plate, the stamping-plate having separable engagement with the section of the plunger operating the same to cause its movement subsequent to the movement of the sealing-plate as the envelop is being stamped and sealed.

7. A stamp-applying machine including a foundation-plate having an opening therein, a movable plate in said opening constituting, with the walls of the opening, a stamp-magazine, a plate above said foundation-plate for pressing the envelop toward the movable plate constituting a part of the magazine, and a gutter near the opening in the said foundation-plate for receiving water, to prevent its access to the stamps in the magazine.

8. An envelop sealing and stamping machine including a foundation-plate, a sealing-plate movable toward and from the said foundation-plate, a stamping-plate movable toward and from the sealing-plate, the envelop to be sealed and stamped being interposed between the sealing-plate on one side and the foundation and stamping plates on the other side, and an actuating element including in its formation a contractible sec-

tion, one section of the actuating element operating the stamping-plate and the other section of the actuating element operating the sealing-plate.

5 9. An envelop sealing and stamping machine including a foundation-plate, a sealing-plate movable toward and from the said foundation-plate, a stamping-plate movable toward and from the sealing-plate, the envelop to be sealed and stamped being interposed between the sealing-plate on one side and the foundation and stamping plates on the other side, and an actuating element including in its formation a contractible section, one section of the actuating element operating the stamping-plate and the other section of the actuating element operating the sealing-plate, the stamping-plate having separable engagement with the section of the actuating element operating the same to cause its movement subsequent to the movement of the sealing-plate as the envelop is being stamped and sealed.

10. An envelop sealing and stamping machine including a foundation-plate, a sealing-plate movable toward and from the said foundation-plate, a stamping-plate movable toward and from the sealing-plate, the envelop to be sealed and stamped being interposed between the sealing-plate on one side and the foundation and stamping plates on the other side, and an actuating element including in its formation a contractible section in the form of a spring, one section of the actuating element operating the stamping-plate and the other section of the actuating element operating the sealing-plate.

11. An envelop sealing and stamping machine including a foundation-plate, a sealing-plate movable toward and from the said foundation-plate, a stamping-plate movable toward and from the sealing-plate, the envelop to be sealed and stamped being interposed between the sealing-plate on one side and the foundation and stamping plates on the other side, and an actuating element including in its formation a contractible section in the form of a spring, one section of the actuating element operating the stamping-plate

plate and the other section of the actuating element operating the sealing-plate, the stamping-plate having separable engagement with the section of the actuating element operating the same to cause its movement subsequent to the movement of the sealing-plate as the envelop is being stamped and sealed.

12. An envelop sealing and stamping machine including a foundation-plate, a sealing-plate movable toward and from the said foundation-plate, a stamping-plate movable toward and from the sealing-plate, the envelop to be sealed and stamped being interposed between the sealing-plate on one side and the foundation and stamping plates on the other side, and an actuating element including in its formation a contractible section in the form of a coiled spring, one section of the actuating element operating the stamping-plate and the other section of the actuating element operating the sealing-plate.

13. An envelop sealing and stamping machine including a foundation-plate, a sealing-plate movable toward and from the said foundation-plate, a stamping-plate movable toward and from the sealing-plate, the envelop to be sealed and stamped being interposed between the sealing-plate on one side and the foundation and stamping plates on the other side, and an actuating element including in its formation a contractible section in the form of a coiled spring, one section of the actuating element operating the stamping-plate and the other section of the actuating element operating the sealing-plate, the stamping-plate having separable engagement with the section of the actuating element operating the same to cause its movement subsequent to the movement of the sealing-plate as the envelop is being stamped and sealed.

In witness whereof I hereunto subscribe my name this 18th day of February, A. D. 1905.

CHARLES W. GRAY.
